US0D1025309S

(12) **United States Design Patent** (10) Patent No.: **US D1,025,309 S**
(45) Date of Patent: ** Apr. 30, 2024

(54) **WASHING NOZZLE**

(71) Applicant: **NGI A/S**, Nørresundby (DK)

(72) Inventors: **Enrico Visconti**, Reinach (CH); **Rune Østergaard Sayk**, Nørresundby (DK)

(**) Term: **15 Years**

(21) Appl. No.: **29/874,905**

(22) Filed: **Apr. 26, 2023**

Related U.S. Application Data

(62) Division of application No. 35/513,807, filed on Dec. 23, 2021 (U.S. filing date under 35 U.S.C. 384), and

(57) **CLAIM**

The ornamental design for a washing nozzle, as shown and described.

DESCRIPTION

FIG. 1 is a perspective view of a washing nozzle showing our new design;

FIG. 2 is another perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

The broken lines of FIG. 4 represent portions of the washing nozzle that form no part of the claimed design.
